LIQUID BOILER

Filed Oct. 1, 1931

Inventor:
William L. R. Emmet,
by *Charles E. T. Ullas*
His Attorney.

UNITED STATES PATENT OFFICE

WILLIAM L. R. EMMET, OF SCHENECTADY, NEW YORK, ASSIGNOR TO GENERAL ELECTRIC COMPANY, A CORPORATION OF NEW YORK

LIQUID BOILER

Application filed October 1, 1931. Serial No. 566,289.

The present invention relates to boilers for generating vapor from liquid, and especially to boilers intended for vaporizing liquids having a high boiling point as compared to water and which may be comparatively heavy. Such a liquid is mercury, mercury vapor now being utilized for driving elastic fluid turbines and for other purposes, such as a heating agent in connection with industrial processes.

The invention relates particularly to boilers of the type such as that disclosed in the application of myself and B. P. Coulson, Jr., Serial No. 306,486, filed September 17, 1928, and has for its object to provide an improved construction arrangement in a boiler of this type.

For a consideration of what I believe to be novel and my invention, attention is directed to the accompanying description and the claims appended thereto.

In the drawing, Fig. 1 is a view partly in section of a boiler structure embodying my invention; Fig. 2 is a detailed sectional view on a larger scale of a single boiler tube, and Fig. 3 is a sectional view taken on the line 3-3 of Fig. 2.

Referring to the drawing, 1 indicates a boiler drum or casing and 2 indicates boiler tubes depending from the lower portion thereof. Each boiler tube 2 comprises an outer tube 3 which at its upper end is fixed in an opening in drum 1 and is welded thereto as indicated at 4, and a core 5 which is located inside the tube 3 and provides a central passage 6 through which the liquid to be vaporized flows to the bottom of the tube, and an annular passage 7 through which the liquid flows upward and in which it is vaporized. Core 5 is held in spaced relation to outer tube 3 by means of projections 8 and 9 formed on the core. Inside drum or casing 1 and located in spaced relation thereto, is a baffle plate 10 provided with openings 11 through which the liquid to be vaporized is

supplied to core passages 6. Baffle plate 10 is held in spaced relation to the adjacent surface of drum 1 by suitable projections 12 which may be in the form of heads of studs threaded into the baffle plate. Associated with the boiler structure are filler blocks 13 which serve to occupy space within the drum so as to decrease the volume which is required to be filled with liquid to be vaporized. 14 indicates lagging for the boiler structure, which lagging may be fixed in place in any suitable manner. Liquid mercury is conveyed through opening 11 to core passage 6 by means of a tube 15, the upper end of which is suitably fastened, as by welding, in the baffle plate opening 11 while the lower end depends some distance into the core and is held positioned relatively thereto by an annular projection or enlargement 16. The construction and arrangement of tube 15 forms the subject matter of the application of Bevis P. Coulson, Jr., Serial No. 478,399, filed August 28, 1930, and assigned to the assignee of the present application and is more particularly described therein.

My present invention relates particularly to the construction of core 5 for use in a boiler tube of the type described.

According to my invention, I construct the core from a plurality of layers of metal which closely engage each other, the metal being one which offers relatively high resistance to the transfer of heat. For this purpose I have found 3½ per cent silicon steel, which has a heat resistance of the order of two and one-half times that of ordinary cold rolled steel, to be satisfactory. The successive layers of the core are formed preferably from a sheet wound spirally on itself and this is the construction illustrated in the drawing wherein 17 indicates the successive layers of the core. The core may be provided with outer and inner walls 18 and 19 between which the wound up layers are located and the whole may be suitably welded together.

as is indicated at 20. The edges of the layers at the upper end of the core are exposed so that the interstices between the layers may become filled with liquid.

5. In a boiler of this type, it is desirable that as little heat as possible be added to the liquid in its flow through down tube passage 6 so that relatively cool liquid is supplied to the bottom of the tube to keep the tip cool, 10 it being understood that the lower end of the tube is subjected to the most intense heat of the fire. By constructing the tube of successive layers of a metal having relatively high heat resistivity, but a small amount of 15 heat will reach the liquid as it flows down through passage 6.

In constructing a laminated core embodying my invention, a certain amount of void is left between the successive layers and this 20 void becomes filled with liquid. In the core of mercury, mercury vapor is a relatively poor conductor of heat, and should the tube become excessively heated the mercury liquid between the laminations would become vaporized, thereby increasing the resistance to 25 heat flow in the core. This functions to resist to a greater extent transfer of heat to the mercury flowing through the down tube, thus insuring that it remains relatively cool 30 in spite of greater heat to which the tube is subjected. As a result, relatively cool liquid is still supplied to the tip of the tube for absorbing heat from it. Thus the liquid between the layers of the core serves as a sort of 35 safety device against abnormal operation of the tube.

What I claim as new and desire to secure by Letters Patent of the United States, is:—

1. In a boiler structure, the combination of 40 a casing and a boiler tube connected to the casing comprising an outer tube and a core in the outer tube having a passage for conveying liquid to the lower end of the outer tube, the wall of said core comprising a plurality of layers of sheet metal in close contact with each other having relatively high 45 heat resistivity.

2. In a boiler structure, the combination of 50 a casing and a boiler tube connected to the casing comprising an outer tube and a core in the outer tube having a passage for conveying liquid to the lower end of the outer tube, the wall of said core comprising a sheet of metal having high heat resistivity spirally 55 wound on itself to form a plurality of layers.

3. In a boiler structure, the combination of 60 a casing and a boiler tube connected to the casing comprising an outer tube and a core in the outer tube having a passage for conveying liquid to the lower end of the outer tube, the wall of said core comprising a plurality of layers of silicon steel in close contact with each other.

4. A tubular core for a boiler tube the wall 65 of which comprises a plurality of layers of

metal of high heat resistivity in close contact with each other.

5. A tubular core for a boiler tube the wall of which comprises a plurality of layers of silicon steel in close contact with each other. 70

6. A tubular core for a boiler tube the wall of which comprises a sheet of metal of high heat resistivity spirally wound on itself to provide a plurality of closely contacting 75 layers.

In witness whereof, I have hereunto set my hand.

WILLIAM L. R. EMMET.
